UNITED STATES PATENT OFFICE.

ABRAM N. LUCAS, OF MILWAUKEE, WISCONSIN.

MEANS FOR DELIVERING AIR-PUMP AND BLOWER EXHAUST TO LOCOMOTIVE-SMOKE-STACKS.

1,329,618.

Specification of Letters Patent.

Patented Feb. 3, 1920.

Application filed April 15, 1915. Serial No. 21,581.

To all whom it may concern:

Be it known that I, ABRAM N. LUCAS, a citizen of the United States, and a resident of Milwaukee, in the county of Milwaukee 5 and State of Wisconsin, have invented certain new and useful Improvements in Means for Delivering Air-Pump and Blower Exhaust to Locomotive-Smokestacks; and I do hereby declare that the following is a full, 10 clear, and exact description thereof, reference being had to the accompanying drawings, and to the characters of reference marked thereon, which form a part of this specification.

This invention relates to a novel arrangement for connecting the exhaust side of an air pump engine and a distributor to the smoke stack of a locomotive engine to conduct and discharge the exhaust material 20 into and through the smoke stack.

Among the objects of the invention is to provide an exhaust for this purpose, so arranged as to deliver the exhaust material into the base of the smoke stack without interfering with the main exhaust from the 25 engine cylinders.

Another object of the invention is to provide an arrangement whereby the exhaust material will be delivered to the smoke stack 30 at a reduced pressure, as compared to prior practice, and distributed throughout the base of the stack in a manner to muffle the exhaust of the air pump engine and the noise of the distributor and to thereby substantially reduce the noise of the exhaust 35 and also to reduce the blowing effect of the air pump exhaust on the fire in the fire box, and thereby facilitate the steaming of the boiler.

A further object of the invention is to provide an arrangement of this character wherein the exhaust material is delivered to the base of the smoke stack and is commingled with the smoke therein in a manner to appreciably quench the sparks and thereby lessen the emission of sparks from the smoke 45 stack, and to also appreciably clear up the black smoke.

A further object of the invention is to provide a device for effecting the improvements hereinabove set forth, the principal portion of which consists of a very simple, readily constructed and easily applied attachment, and to provide means whereby 50 the connection of the pump exhaust and dis-

tributer pipe thereto are all outside connections and, therefore, readily accessible.

The invention has for further objects to otherwise improve and simplify the connection of exhaust devices to the smoke stack, 60 and the invention consists in the details and arrangements of the parts hereinafter described and more fully set forth in the appended claims.

In the drawings:

Figure 1 is a partial side elevation of a locomotive boiler showing my invention applied thereto.

Fig. 2 is an enlarged axial section of the base of the smoke stack, the smoke arch saddle and my improved distributing and muffling ring therebetween.

Fig. 3 is a sectional detail of an automatic drain valve which is incorporated in the pump exhaust and distributor pipes.

Fig. 4 is a view similar to Fig. 2, showing a modification.

Fig. 5 is a horizontal section of a segment of the muffling and distributing ring, showing the exhaust and distributor pipe 80 connections thereto.

As shown in the drawings, 10 designates a locomotive boiler, 11 an air pump thereon which is connected to the air brake system in any suitable manner, 12 the usual smoke stack and 13 a distributor arranged at the rear end of the boiler at the engineer's cab, not shown. The distributor is connected by a pipe 14 with the smoke stack 12 to deliver steam thereto to increase the draft on 85 the fire in the fire box. The engine of the air pump 11 is connected by a pipe 11^a with the smoke stack to discharge its exhaust thereinto.

Referring now to the features of my invention which relate to the means for discharging the exhaust material into the smoke stack, and calling attention first to the form of device shown in Fig. 2, 15 designates, what may be termed, a distributing 95 and muffling ring which is formed with an annular chamber 16. Said ring, as shown in Fig. 2, has the form of a separate casting that is adapted to be interposed between the arch saddle 17 and the lower end or base of the smoke stack 12. In the form of construction shown in Fig. 2 the base of the smoke stack is provided with an annular depending flange 18 which is adapted to fit 100 into an annular rabbeted portion 19 of the 105 110

arch saddle 17, in the absence of my improved distributing and muffling ring. In adapting said ring to the saddle and smoke stack I may provide the ring with a depending 5 annular portion or flange 20 which is adapted to fit within the rabbet 19 of the saddle, and also provide said ring at its upper side with an upstanding flange 21 into which the annular flange 18 of the smoke stack 10 base is adapted to fit. The said ring, therefore, surrounds the path of the smoke in its passage through the smoke stack and is located exterior to said path. Moreover, it may be made sufficiently massive to withstand 15 long wear due to the impingement of cinders thereagainst.

The parts are fastened together by means of screw bolts 22 which extend loosely through openings in a radial flange 23 at the 20 base of the smoke stack and enter at their lower, screw-threaded ends into screw-threaded openings in the saddle. In applying my invention to the smoke stack, it will be necessary, therefore, to merely provide 25 longer screw bolts 22 than used in the standard arrangement.

The distributing and muffling ring is provided at its inner side, near its top, with an 30 annular discharge nozzle 24 having the form of a narrow slit. The said nozzle is arranged at such an angle, relatively to the axis of the smoke stack, as to discharge the 35 exhaust material into the smoke stack in the form of a conical hollow jet, concentric to the axis of the smoke stack, through which jet the smoke and main exhaust from the cylinders must pass on their way upwardly through the stack. The areas of the annular opening 16 of the distributing and muffling 40 ring and the nozzle 24 are such, relatively to the areas of the pipes 14 and 11^a, that the pressure of the exhaust material is reduced in passing through said annular opening 16, so that it is discharged through the nozzle 45 24 at a substantially reduced pressure, but with sufficient force to be commingled with the ascending smoke column and to exercise a moderate draft producing effect in the smoke stack.

50 The ring 15 is provided at one side thereof with externally screw-threaded nozzles 26, 27, respectively, to which are respectively connected the pipes 14 and 11^a leading from the distributor and air pump engine, respectively, whereby said pipes discharge into the annular chamber 16 of the distributing and muffling ring.

The proportioning of the distributing and muffling ring opening and nozzle areas relatively to the areas of the exhaust pipes 14 and 11^a, hereinbefore referred to, taken in connection with the arrangement whereby the jet is discharged from an annular nozzle that surrounds the smoke column and which 55 is disposed concentrically to the axis of the

smoke stack, has the important advantage of disturbing to a minimum extent the main exhaust of the engine cylinders through the smoke stack, and also has the effect of thus distributing the exhaust material to the 70 smoke stack without unduly increasing the draft on the fire in the firebox. Said arrangement is also advantageous in that the exhaust material is discharged into the smoke stack comparatively noiselessly, 75 whereby the operation of the device may be made to comply with anti-noise ordinances of various cities. Furthermore, the arrangement whereby the exhaust material is discharged in a hollow conical jet which surrounds the ascending column of smoke in the smoke stack, and which intersects all parts of said column, is advantageous inasmuch as the moisture contained in said exhaust material has the effect to dampen the products 80 of combustion and to sensibly extinguish the burning sparks carried thereby.

In Fig. 4 I have shown an arrangement wherein the smoke arch saddle, designated 90 therein by 28, is formed to provide therein an annular chamber 29 having an upwardly, inwardly inclined annular nozzle 30, whereby the saddle and muffling and distributing ring may be made of a single casting. When thus constructed the saddle may be exteriorly shaped to receive the base of the smoke stack 12 in the usual manner, said smoke stack being attached to the saddle by means of short screw bolts 31. In this construction the jet of exhaust material is discharged into the smoke stack at a plane below that shown in Fig. 2. Obviously, if desired, the distributing and muffling ring may be supported within the smoke arch in any suitable manner below and concentric to the 100 opening to the smoke stack, or the distributing and muffling chamber may be formed in the base of the smoke stack.

As an additional improvement the distributing and muffling ring may be provided 110 with a third socket 32 to receive the pipe of a stationary distributor located in a round-house or other place where a locomotive may be fired to produce an initial draft to start a fire in the fire box before the boiler is 115 steamed.

As a further improvement the pipes 14 and 11^a which extend directly from the muffler and distributing ring to the air pump and distributor are arranged in such manner that the lowest parts of said pipes are located closely adjacent to their connections with said devices. Contained within said pipes and located closely adjacent to the distributor and air pump, respectively, 120 are drain valves 33 which are arranged to automatically drain water of condensation from said pipes, said drain valves being disposed at the lowest parts of the pipes.

A convenient form of automatic drain 130

valve is shown in Fig. 3. As therein shown, it consists of a body 35 having the form of a coupling to connect adjacent sections of the pipe in which it is incorporated. The 5 said body 35 is provided with a hollow depending, internally screw-threaded neck 36. 37 designates a plug which is exteriorly screw-threaded to engage the interior screw-threads of the neck 36 and depends from 10 said neck. Said plug is provided with one or more drain openings 38 through which water is drained from the valve. Said openings 38 are adapted to be closed by a valve piece 39 which has the form of a disk, as 15 herein shown, and is adapted, when closed, to rest upon the upper end of the plug 37 and to close the drain openings 38. Said valve piece is provided with a depending stem 40 which extends downwardly through 20 a central guide opening 41 of the plug. The lower end 42 of the stem is reduced to provide a downwardly facing shoulder 43 and the lower end of the central opening 41 of the plug is likewise reduced to constitute an 25 upwardly facing shoulder 44. A compression spring 45 surrounds the reduced end of the stem and is interposed between said shoulders 43, 44 and acts to normally hold the valve piece in its open position; the 30 opening movement of the valve being limited by a nut 46, or other shoulder, on the lower end of the stem and bearing against the lower face of the plug 37. When the 35 pressure in the pipe 14 is equalized with the atmospheric pressure, the spring 45 holds the valve piece 39 in its open position, as indicated in Fig. 3. Pressure within the pipe 14, such as occurs upon the passing of exhaust material therethrough, serves to close 40 the valve and prevent leakage of exhaust material therefrom. The area of the valve piece is such, with respect to the strength of the spring 45 that a very slight rise of pressure in the pipe serves to promptly close the 45 valve against the passage of exhaust material.

It will be understood that the invention is not limited to the structural details herein

shown, but that it is my intention to claim all that is inherently novel in the disclosure 50 herein.

I claim as my invention:—

1. The combination with the smoke stack of a locomotive boiler and smoke arch saddle thereof, of a separately formed, removably 55 attached fitting between the stack and arch saddle and above the boiler and formed to interfit with standard saddles and smoke stacks of a locomotive, and provided with an annular chamber which surrounds the 60 stack smoke conduit, said fitting being provided with a connection external to the boiler for exhaust and distributor pipes and being provided with an internal annular nozzle to direct exhaust material into the 65 smoke stack.

2. The combination with the smoke arch of a locomotive boiler, the smoke arch saddle thereabove and the smoke stack, of a separately formed fitting between the stack and 70 the saddle formed with an annular chamber and provided with an exhaust receiving opening and with an internal annular nozzle 75 exterior to said fitting to direct exhaust material into the stack, and fastening bolts to fasten the stack to the saddle and to clamp the fitting between the stack and saddle.

3. The combination with the smoke stack and the smoke stack arch saddle of a locomotive boiler of a nozzle fitting interposed 80 between the base of said stack and said smoke arch saddle, provided on its upper and lower sides with annular flanges or shoulders to interfit with annular shoulders on said stack and saddle respectively, 85 and provided with an annular nozzle and with an external exhaust receiving opening.

In testimony, that I claim the foregoing as my invention I affix my signature in the presence of two witnesses, this 7th day of April, A. D. 1915.

ABRAM N. LUCAS.
